Primary Examiner — Sandra Morris(74) *Attorney, Agent, or Firm* — Knobbe Martens Olson & Bear LLP(57) **CLAIM**

The ornamental design for a bottle, as shown and described.

DESCRIPTION

FIG. 1 is a front and top perspective view of a bottle embodying my new design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof; and,

FIG. 7 is a bottom plan view thereof.

Portions shown in phantom lines are for illustrative purposes only and form no part of the claimed design.

1 Claim, 4 Drawing Sheets(56)
